UNITED STATES PATENT OFFICE

2,042,000

TYPEWRITING MACHINE

George F. Handley, Glendale, N. Y., assignor to
 Royal Typewriter Company, Inc., New York,
 N. Y., a corporation of New York

Original application December 29, 1934, Serial
 No. 759,779. Divided and this application De-
 cember 16, 1935, Serial No. 54,732

2 Claims. (Cl. 197—145)

This invention relates generally to new and useful improvements in typewriting or like machines, although more particularly to means for removably mounting the platen on the carriage. 5 This application constitutes a division of my parent application Serial No. 759,779, filed Dec. 29, 1934, for improvements in typewriting machines. The principal object of this invention is to provide a quick retractile bearing for the end 10 of the platen shaft opposite the ratchet wheel and which may be easily installed on a commercial carriage without the necessity of slotting the end plate or employing the latch or forming an angular groove in the platen axle as is shown in 15 the Myers Patent 1,496,940, June 10, 1924.

In the drawing:

Figure 1 is a plan view of a portion of a typewriter carriage and platen and showing the application of my invention, a portion thereof being shown in section, and

Figure 2 is a front elevation of the structure shown in Figure 1, parts thereof being shown in elevation.

Referring to the accompanying drawing, I have 25 disclosed my invention as being applied to a typewriting or like machine which includes a carriage A having right and left end plates 5 and 6, the latter being provided with the usual laterally extending shelf 7. Located between these end 30 plates and rotatably supported thereon is a readily removable cylindrical platen B.

Journaled in the end plate 6 is a spindle 8 having a handwheel 9 secured thereto. This spindle is held against endwise movement. The 35 inner end of this spindle projects inwardly between the end plates 5 and 6 and fixed on the inwardly projecting end is the usual line spacing ratchet wheel 10 and a cup-shaped clutch element 11. The inner end of the spindle is provided with an inwardly extending lateral slot 12. The spindle is provided with an axial bore 13 and slidably mounted in this bore is a push rod 14. A stop 15 cooperates with the rod 14 through the 40 medium of a finger-piece 16 to limit the outward movement of said rod, the rod being normally urged outwardly by a coil spring. Secured to the adjacent end of the platen B is a head 18 having an outwardly extending hollow boss 19 for receiving the inner end of the spindle 8. The 45 boss 19 is provided with an inwardly extending radial slot 20. A clutch element 21 is supported on the boss 19 for movements toward and from the same by means of pins 22. The clutch element 21 is in the form of a disc and is provided 50 with clutch teeth 23 on its periphery. This

clutch element 21 is adapted to normally engage clutch teeth 24 formed on the inner face of the cup or clutch element 11. Coil springs 25 are mounted in the platen B for cooperation with the pins 22 to normally and yieldably hold the 5 clutch element 21 in positive driving engagement with the clutch element 11 whereby the ratchet wheel 10 and the platen B will be normally coupled so that line spacing movement imparted to the ratchet wheel by the usual line spacing lever 10 will be transmitted to the platen. The clutch disc 21 is provided with a concentric opening 26 to receive the outer end of the boss 19, and a split disc 27 which is attached to the clutch disc 21 is provided with a tongue 27a which projects 15 radially to the center of said opening. This tongue 27a normally projects through the slot 20 of the boss 19 and into the slot 12 of the spindle 8 and into position to be engaged by the inner end of the push rod 14. Upon inward movement 20 of the push rod 14, the tongue 27a will be engaged thereby and the clutch element or disc 21 will be moved inwardly toward the platen to thereby disconnect the clutch element and consequently disconnect the platen B from the 25 ratchet wheel 10 whereby the platen may be freely rotated in either direction. The above construction is all disclosed in the Myers Patent 1,496,940 referred to above.

When it is desired to remove the platen, the 30 right hand end thereof will be disconnected from the end plate 5 of the carriage, the right hand end of the platen will then be swung upwardly until the same clears the end plate 5, and the platen can be readily removed from the carriage. 35

The right hand end of the platen B is removably supported on the end plate 5 of the carriage by the following means: The end plate 5 is provided with a closed opening 29 and fitted into this opening and rigidly secured to the end 40 plate is an outwardly extending bearing 30. The adjacent end of the platen B terminates in spaced relation to the end plate 5 and rigidly attached to this end of the platen by means of a flange 31, is a bearing sleeve E having a portion 45 32 extending outwardly from the platen toward the end plate 5 and an inwardly extending portion 33 positioned in an axial bore 34 formed in the end of the platen. Normally positioned in the aligned bearing 30 and sleeve E is a retractile 50 bearing shaft F for the adjacent end of the platen. By retracting this bearing shaft until the inner end thereof is free from the bearing sleeve E, the adjacent end of the platen will be freed and the platen can then be readily removed. The 55

outer end of the shaft F is provided with a hand-wheel 45. In order to normally retain the bearing shaft F in its operative position, I have provided a latch connection between the shaft and the sleeve. To this end, the shaft F is provided with a reduced inner end which is slotted longitudinally as at 59 to form resultant spring clamping arms 60, 60. The opposed inner faces of these arms are conjointly formed with a transverse seat 61 for receiving a locking pin 44 which extends across the inner end of the bearing sleeve E, the diameter of the seat being substantially equal to the diameter of the pin, and the seat being located intermediate the ends of the slot. Thus when the shaft F is inserted into the sleeve E, the arms 60, 60 will engage the pin 44 and spread slightly until the pin registers with the seat 61 at which time the arms will retract and frictionally retain the shaft against longitudinal movement relative to the platen.

From the foregoing, it will be observed that whenever it is desired to remove the platen, the right hand end of the platen is first disconnected from the carriage by withdrawing the bearing shaft F, and then the right hand end of the platen is swung upwardly and then bodily removed from the carriage, the construction at the left hand end of the carriage permitting its ready disconnection therefrom.

30 I claim:

1. In a typewriting or like machine, the com-

bination with a typewriter carriage having end plates, one of said plates having a bearing opening therein, a platen having one end removably supported by the other side plate, a bearing sleeve attached to the other end of the platen and having a transverse pin mounted therein, and a retractile bearing shaft for the last mentioned end of the platen mounted in said side plate opening and in said sleeve, the inner end of the shaft being transversely slotted to form resultant 10 clamping arms for frictionally engaging said transverse pin.

2. In a typewriting or like machine, the combination with a typewriter carriage having end plates, one of said plates having a bearing opening therein, a platen having one end removably supported by the other side plate, a bearing sleeve attached to the other end of the platen and having a transverse pin mounted therein, and a retractile bearing shaft for the last mentioned end 15 of the platen mounted in said side plate opening and in said sleeve, the inner end of the shaft being transversely slotted to form resultant clamping arms for frictionally engaging said transverse pin, the inner faces of said clamping arms being 20 conjointly formed intermediate their ends with a transverse seat for receiving said transverse pin, the diameter of said seat being substantially equal to the diameter of the transverse pin.

30

GEORGE F. HANDLEY.
